US00D950399S

(12) **United States Design Patent** (10) Patent No.: **US D950,399 S**
(45) Date of Patent: **** May 3, 2022**

(54) **ENVIRONMENTAL DETECTION DEVICE**

(71) Applicant: **Ultimo Global Holdings, LLC**,
Wilmington, DE (US)

(72) Inventor: **Phillip Nathan Thornberry**, Carmel,
IN (US)

(73) Assignee: **Ultimo Global Holdings LLC**,
Wilmington, DE (US)

(**) Term: **15 Years**

(21) Appl. No.: **29/725,047**

(22) Filed: **Feb. 21, 2020**

(51) LOC (13) Cl. **10-05**

(52) U.S. Cl. **D10/52**
USPC ....

CLAIM

The ornamental design for an environmental detection device, as shown and described.

DESCRIPTION

FIG. 1 is a front, right, perspective view showing my new design;

FIG. 2 is a front side view thereof;

FIG. 3 is a rear side view thereof;

FIG. 4 is a left side view thereof;

FIG. 5 is a right side view thereof;

FIG. 6 is a top view thereof; and,

FIG. 7 is a bottom view thereof.

The broken lines illustrate portions of the environmental detection device and form no part of the claimed design.

1 Claim, 5 Drawing Sheets
